LAGGING FOR REELS

Arthur A. Bureau, Chicago, Ill., assignor to Western Electric Company, Incorporated, New York, N. Y., a corporation of New York

Application September 12, 1940, Serial No. 356,446

5 Claims. (Cl. 206—59)

This invention relates to lagging for reels, and particularly to lagging for reels used for storing and transporting heavy material, such as lead covered cable.

An object of the present invention is the provision of lagging which is of the required structural strength, economical to manufacture, and durable in service.

In accordance with the above object, one embodiment of the invention contemplates metal lagging comprising a series of sheet metal channel box-like lags placed side by side across the outer peripheries or rims of spaced metal reel heads to form a complete enclosure of the cable storage space of the reel. Each individual lag is formed from a suitably shaped integral blank subsequently pressed into a box-like structure having two thicknesses of metal throughout the width and length of the side arms, the metal of the arms being bent inwardly and provided with rounded edges which rest upon the peripheral surfaces of the spaced head rims and extend from one outer peripheral edge to the other of the rims. The edges of the inner thicknesses of metal of the side arms abut the inner surface of the web connecting the side arms. The ends of the web are provided with bent over portions welded to the inner end edges of the side arms which serve to close up the ends of the channel and freely extend slightly within the peripheral surfaces of the rims at their outer edges, thus preventing longitudinal shifting of the lag when positioned on the reel heads. Tensioned steel retaining bands extending around the enclosing lags and retained under tension serve to secure the lagging to the reel.

Other objects and advantages of this invention will more fully appear from the following detailed description taken in connection with the accompanying drawing, in which

Fig. 1 is a fragmentary view in side elevation of a metal cable reel provided with the improved lagging of this invention;

Fig. 2 is an enlarged vertical section taken on the line 2—2 of Fig. 1;

Fig. 3 is an enlarged vertical section taken on the line 3—3 of Fig. 2, and

Fig. 4 is a perspective view of one of the improved lags.

Referring now to the drawing, a preferred form of lagging embodying the invention is illustrated, for example, in conjunction with a cable reel comprising a pair of spaced heads 10, interconnected by a drum 11 (Fig. 1) for holding a lead covered cable 12, or other heavy material that may

be wound thereon. The cable reel itself may be of any suitable construction, although a welded all-metal construction is preferred. In the construction illustrated, the heads each comprise an inner annular channel member 13, an outer annular rim 14 concentric therewith, channel spokes 15 extending between the inner annular member and the rim and welded thereto, and an annular metallic disc or head sheet 16 welded to the spokes on the side facing the drum.

The spokes are notched at their outer ends, as shown in Fig. 2, to receive outwardly turned outer flanges 17 of the head sheets, which may be welded to the under side of the rims 14. The spokes are also notched at their inner ends to receive the ends of the drum 11 and outwardly turned inner flanges 21 of the head sheets, which together with the drum, may be welded to the annular channel 13.

The improved metal lagging embodying the invention comprises a plurality of channel box-like type lags 25 of uniform size and construction and sufficient in number so that when placed side by side on the rims 14 and lengthwise across the width of the reel, as shown in Figs. 1 and 2, a complete covering or enclosure is provided for the cable storage space of the reel. To form the lag 25 a suitably shaped blank is first punched from sheet metal and then formed in a number of pressing operations into a channel box-like type structure shown in perspective in Fig. 4 and in detail in Figs. 2 and 3.

Each lag 25 comprises a flat web portion 26 interconnecting depending side arms or flanges 27 each having two thicknesses of metal throughout their width and length. The inner thickness of metal in each side arm is formed by providing extensions of sufficient depth in the side arm portions of the blank and then bending such extensions inwardly along a line substantially midway of its depth until it lies flat against the outer thickness of metal and abuts the inner surface of the web 26. An outer rounded edge 28 is thus formed along the bending line of the two thicknesses of metal in the side arms 27 which edges at their opposite ends rest upon the peripheral surfaces of the spaced reel head rims 14. End walls 30 for the channel box-like lag 25 are formed by providing extensions of sufficient length at the ends of the web portion of the blank and then bending such extensions inwardly to abut the end edges of the side arms 27 after which they are welded, as indicated at 31, to the inner end edges of the side arms 27, thus connecting the side arms and increasing the rigidity

of the lag. The end walls 30 are of such depth that they extend past the rounded edges 28 of the side arms 27 which rest upon the peripheral surfaces of the reel head rims 14 and slightly within the latter surfaces, as clearly shown in Figs. 2 and 3 at 32. The extensions of the end walls 30 at 32 serve to prevent longitudinal shifting of the lag when positioned on the reel heads. To retain the improved reel lags in place on and encircling the reel metallic bands 33 are provided which are suitably tensioned and tied by a member 34 secured to overlapping ends of the bands.

It is to be understood that the invention is not limited to the specific embodiment herein illustrated and described except insofar as is defined by the appended claims.

What is claimed is:

1. In combination, a reel having spaced heads, a lagging for said reel, each lag comprising an integral inverted box-like member of sheet metal having a top portion forming an outer surface, opposite reinforced side walls extending from said top portion each comprising a plurality of thicknesses of metal, lower edges of said side walls adapted to transversely span and rest upon the peripheries of the spaced reel heads, and opposite end walls extending from said top portion and arranged outside of said side wall lower edges and overlapping and contacting the outer peripheral edges of the reel heads to prevent shifting of the lag transversely on the reel heads.

2. In combination, a reel having spaced heads, a lagging for said reel, each lag comprising an integral inverted box-like member of sheet metal having a top portion forming an outer surface, opposite reinforced longitudinally extending side walls extending from said top portion each comprising a plurality of thicknesses of metal, lower edges of said side walls adapted to transversely span and rest upon the peripheries of the spaced reel heads and having their end edges in substantial alignment with outer peripheral edges of the reel heads, and opposite end walls extending from said top portion and arranged outside of said side wall lower edges and overlapping and contacting the outer peripheral edges of the reel heads to prevent longitudinal shifting of the lag on the reel heads.

3. In combination, a reel having spaced heads, a lagging for said reel, each lag comprising 50 an integral inverted box-like member of sheet

metal having a top portion forming an outer surface, opposite reinforced side walls extending from said top portion each having two thicknesses of metal, one thickness of metal being bent upwardly, lower edges of said side walls adapted to transversely span and rest upon the peripheries of the spaced reel heads, and opposite end walls extending from said top portion and arranged outside of said lower side wall edges and overlapping and contacting the outer peripheral edges of the reel heads to prevent shifting of the lag transversely on the reel heads.

4. In combination, a reel having spaced heads, a lagging for said reel, each lag comprising an integral inverted box-like member of sheet metal having a top portion forming an outer surface, opposite reinforced side walls extending from said top portion each having two thicknesses of metal throughout one thickness of metal being bent inwardly and upwardly relative to the outer thickness of metal and having its upper edge arranged adjacent the inner surface of said top portion, lower edges of said side walls adapted to transversely span and rest upon the peripheries of the spaced reel heads, and opposite end walls extending from said top portion and arranged outside of said lower side wall edges and overlapping and contacting the outer peripheral edges of the reel heads to prevent shifting of the lag transversely of the reel heads.

5. In combination, a reel having spaced heads, a lagging for said reel, each lag comprising an integral inverted box-like member of sheet metal having a top portion forming an outer surface, opposite reinforced side walls extending from said top portion each having two thicknesses of metal throughout, one thickness of metal being bent inwardly and upwardly relative to and abutting the outer thickness of metal and having its upper edge arranged adjacent the inner surface of said top portion, lower edges of said side walls formed by bending the two thicknesses of metal being rounded and adapted to span and rest upon the peripheries of the spaced reel heads, and opposite end walls extending from said top portion and beyond said lower side wall edges, said end walls having their inner surfaces abutting the ends of the side walls and being united thereto by welding.
